ROTARY DRUM SNOWPLOW

Franz F. Wallack, Bruck an der Glocknerstrasse,
AustriaApplication October 31, 1950, Serial No. 193,119
In Austria September 13, 1947

1 Claim. (Cl. 37—43)

1

This application is in part a continuation of application Serial No. 141,633, filed February 1, 1950, now abandoned.

This invention relates to a rotary drum snow plow, which is adapted to form part of a motor vehicle built for the purpose or which may be in the form of an attachment for a motor truck, locomotive, street car or the like.

The object of the invention is to provide a plow of the type having a pair of vertically disposed cutter drums which are adapted to clear the snow from the highways irrespective of the condition of snow, thereby maintaining open highways for traffic at all seasons of the year.

Another object is to construct a plow so that snow of moderate elevation may be removed in one single process on a comparatively large area.

A further object of the invention is to devise a snow plow which will remove high side-walls previously built up by plows, especially insofar as those side-walls lie in the road way.

Another object of the invention is to construct a snow plow so that vertical snow-walls extending in the longitudinal direction of the road may be removed readily.

Still another object is to reduce the number of parts of the snow plow which move and discharge the snow.

Other objects will be apparent to those familiar with this art and with the difficulties encountered in it, some of which arise from the very wide variation in weight of snow per unit volume, compactness and moisture content.

The accompanying drawings show two forms of this invention which were built for the purpose of trying out in actual operation the features claimed herein, and to determine their merit by comparison with other equipment.

In the drawings:

Fig. 1 is a side elevation of my improved snow plow, with parts of the same broken away and in section.

Fig. 2 is a top plan view of the same with parts of the casing broken away.

Fig. 3 is a fragmentary front elevation of my improved snow plow.

Fig. 4 is a section on an enlarged scale through one of the cutter drums along the plane of the line IV—IV of Fig. 5.

Fig. 5 is a section through one of the cutter drums along the plane of the line V—V of Fig. 4.

Fig. 6 is a vertical section through the blower along the plane of the line VI—VI of Fig. 7.

Fig. 7 is a horizontal section through the blower along the plane of the line VII—VII of Fig. 6.

2

Fig. 8 is a section similar to that of Fig. 5 but showing a modified form of a cutter drum.

Fig. 9 shows diagrammatically the division of the drum into different working sectors.

5 Referring for the present to Figs. 1 and 2, wherein the general assembly is shown, 1 represents a frame to which all the parts of the device are attached or mounted. The frame 1 is supported by two pairs of front wheels 2 and 3 and one rear wheel 4, the latter being rotatable around a vertical axle 5 for the purpose of steering the vehicle.

10 The engine 6 driving the vehicle is mounted on the frame 1 and drives, through a horizontal shaft 7 and the usual gearings, the pairs of front wheels 2 and 3. The driver's cab 8 is also arranged on the frame 1, the necessary clutch devices being arranged in said cab.

15 The two lateral portions of the frame 1 are interconnected by means of a pin 9 onto which two supports 10 are pivoted, said supports 10 being interconnected by a tubular member 24 also pivoted onto said pin 9. Each of the supports extends to the front of the vehicle and is provided with a vertical portion 16 and a forwardly projecting horizontal portion 15 and also carries a downwardly bent support 17 for bearing the cutter drums. Each horizontal portion 15 of the support 10 carries a pin 11 onto which a piston 12 is pivoted and each front end of the lateral portions of the frame 1 carries a pin 13 onto which a cylinder 14 is pivoted. The cylinder 14 is filled with oil and serves for raising and lowering the piston 12 which slides therein. Thereby the front ends of the supports 10 and also the cutter drums can be raised and lowered relative to the roadway.

20 A horizontal shaft 19 rotates in bearings 18 arranged onto the horizontal portions 15 of the supports 10, which shaft is driven by a cutter-driving engine 20. The shaft 19 carries a sprocket wheel 21 which drives by means of a sprocket chain 22 a sprocket wheel 23 mounted on the horizontal shaft 19. The horizontal shaft 19 operates the two cutter drums by means of bevel gears 26 and 27, a horizontal shaft 28 and bevel gears 30 and 31. The horizontal shaft 28 extends transversely to the direction of travel of the vehicle and is journaled in bearings 29 provided on the front ends of the horizontal portions 15 of the supports 10. Each cutter drum is provided with a vertical shaft 32 on which the bevel gear 31 is mounted. The lower ends of the cutter shafts 32 are rotatively supported in bearings 33 arranged at the front ends of the downwardly

bent supports 17. Each cutter shaft 32 bears between the supports 15 and 17 an upper disc 35 and a lower disc 36 on which the cutter blades as well as the guide blades are secured.

Referring to Figs. 4 and 5, three cutter blades 37 are provided at the circumference of each cutter drum, which cut or shave off the snow when the cutter drum is in rotation. The cut-off snow then enters the interior of the cutter drums, where three guide blades 42 are arranged. The inner end 42a of each guide blade 42 is pivotally connected by a hinge pin 39a to a radial projection of a rotary core member 38. Bores 40 are provided in the upper and lower discs 35 and 36 of the cutter drums and bolts 39 extend through said bores 40 and into bores in the ends of pins 39a to adjust the position of the core member relative to the discs 35 and 36 and thereby also to the cutter blades 37. Moreover, bores 43 are provided in the upper and lower discs 35 and 36, at a larger radius, and pins 45 extend into these bores and through bores 44 provided in the guide blades 42 to alter the position of the guide blades relative to the upper and lower discs 35 and 36 and to the core member 38.

The cutting edges of the cutter blades 37 may consist either of straight edges parallel to or inclined towards the axis of rotation, or of broken or curved edges. The guide blades form troughs, the outwardly concave bottoms of which extend close to the drum shaft. The radius r_2 of the outermost edges of the guide blades 42 is smaller than the radius r_1 of the cylinder defined by the cutting edges of the revolving cutter blades.

The two cutter drums are partially enclosed by a casing 46 extending forwardly to a plane substantially coincident with a vertical plane passing through the axes of the cutter drums. The casing 46 comprises an enlarged forward section having a flaring mouth portion which extends substantially the full width of the plow, side wall portions 46a curving rearwardly and inwardly from the mouth and rear wall portions 46b extending inwardly from the side wall portions, and a central restricted section which extends rearwardly from the inner ends of the rear wall portions 46b of the forward section and is shaped to form a blower or fan-wheel housing 46c. The two cutter drums are arranged in close proximity to one another in the enlarged forward section of the casing and extend across substantially the entire width of the mouth portion, being rotatable about vertical axes disposed in a vertical plane normal to the direction of travel of the plow. A fan-wheel 47 is located in the blower housing 46c formed by the rearwardly extending central portion of the casing and is mounted on a horizontal shaft 48 which is parallel to, and spaced rearwardly from, the vertical plane containing the axes of the cutter drums. The central plane of rotation of the fan-wheel 47 is thus in a longitudinal vertical plane which passes midway between the axes of the cutter drums. The forward portion of the fan-wheel projects forwardly into the enlarged forward section of the casing 46 and extends into the converging space between the rear portions of the cutter drums. The fan-wheel shaft 48 is journaled in bearings 49 located on the supports 10 and is driven through a speed-varying gearing 50 by an engine 51. The fan-wheel preferably consists of a middle portion 52 onto which a number of curved fins or buckets 53 are fastened, the outer ends of the fins being free.

The blower housing 46c is provided with a ver-

tical discharge tube 54 arranged above the fan-wheel in such a manner that it lies above the fins or buckets 53 behind the shaft 48 of the fan-wheel 47. A curved chute 57 is connected by means of flanges 55 and 56 with the upper end of the tube 54 and may be swung about a vertical axis so as to discharge the snow toward either side of the road.

In the modified form of the cutter drums shown in Fig. 8, the ends of the guide blades 42 cannot be adjusted but are rigidly connected with the core member 38. Therefore, in this modification, only the blades and core member as a whole can be adjusted. For this purpose, holes 60 are provided in the upper and lower discs and bolts (not shown) extend through these holes and into bores provided in one of the blades 42.

In the operation of the snow plow, the cutter drums are rotated rapidly in opposite directions with the front portions of the cutter drums moving outwardly away from each other. As the vehicle advances, the cutter blades 37 on the front portions of the cutter drums cut into the snow. The lower ends of the cutter blades 37 are located close to the surface of the road and will effectually remove the snow therefrom, even when the same is hard, frozen or icy. The cutting action of the blades 37 occurs in the sector *a* in Fig. 9. The snow enters the interior of the cutter drum and engages the guide blades 42 close to the shaft 32. The guide blades 42 receive the snow and convey it away from the central longitudinal plane of the plow and around to the rear portions of the cutter drums (sector *b*, Fig. 9). At the same time, the snow picks up velocity and is moved by centrifugal force toward the circumferences of the cutter drums. As the snow reaches sector *c* (Fig. 9), it is thrown toward the central longitudinal vertical plane 40 of the plow, being guided by the casing into the opposite sides of the fan-wheel 47 which ejects the snow through the discharge tube and blows it a considerable distance in a direction determined by the chute 57. Thus the snow is fully ejected from the cutter drums before reaching the sector *d* in which the drums closely approach one another. Jamming or packing of snow between the cutter drums is thereby avoided. It will further be seen that, in the arrangement according to the invention, it is possible to use a single fan-wheel for the two cutter drums, the snow being discharged by the cutter drums into the opposite sides of the forward portion of the fan-wheel.

The speed of rotation of the cutter drums and of the fan-wheel depends on the conditions of the snow, the desired distance to which the snow has to be thrown out, etc. In an example of the machine, the cutter drums rotate at 120 revolutions per minute, whereas the speed of the fan-wheel can be changed from 120 to 350 revolutions per minute. The axis of the fan-wheel is disposed at about two-thirds of the height of the cutter drums and the diameter of the fan-wheel is greater than said height.

It will be apparent that many changes may be made in the details of construction without departing from the spirit of the invention. For example, the method of driving the various moving parts may be considerably varied. In the mechanism, "break pins" or other safety devices may be employed to prevent damage to the apparatus in case of jamming through unbreakable objects being drawn into the apparatus.

What I claim is:

In a snow plow, a casing comprising an enlarged forward section having a flaring mouth portion extending substantially the full width of the plow, side wall portions curving rearwardly and inwardly from said mouth and rear wall portions extending inwardly from said side wall portions, and a central restricted section extending rearwardly from the inner ends of said rear wall portions and shaped to form a blower housing having a discharged opening, a pair of cutter drums disposed in the enlarged forward section of the casing and rotatable about vertical axes disposed in a vertical plane normal to the direction of travel of the plow, said cutter drums being in close proximity to one another and extending across substantially the entire width of the mouth of said forward section, means for rotating said cutter drums in opposite directions with the front portions of the cutter drums moving outwardly away from each other, a fan-wheel in said blower housing rotatable about a horizontal axis parallel to, and spaced rearwardly from, said vertical plane, the central plane of rotation of the fan-wheel being in a longitudinal vertical plane midway between the axes of the cutter

drums, the forward portion of said fan-wheel projecting forwardly into the enlarged forward section of the casing and extending in between the peripheries of the rear portions of said cutter drums, and means for driving the fan-wheel, whereby snow engaged by said cutter drums is carried by the front portions of the cutter drums away from said longitudinal vertical plane and then is thrown toward said longitudinal vertical plane by the rear portions of the cutter drums, being guided by the casing into the opposite sides of the forward portion of the fan-wheel.
